UNITED STATES PATENT OFFICE.

LEONIDAS E. PONTON, OF FRISCO, OKLAHOMA.

SANITARY CASKET.

1,184,125.

Specification of Letters Patent. Patented May 23, 1916.

Application filed April 19, 1915. Serial No. 22,269.

To all whom it may concern:

Be it known that I, LEONIDAS E. PONTON, citizen of the United States, residing in Frisco, county of Pontotoc, State of Oklahoma, have invented new and useful Improvements in Sanitary Caskets, of which the following is a specification, reference being had to the accompanying drawings.

My invention relates to metal burial caskets, and has for an object the production of a burial casket which shall be cheap and economical to manufacture, strong to resist the pressure which may be brought to bear upon it from any direction or source, and resistant to the action of the elements, and which may be hermetically sealed.

A further object is to produce such casket in the most convenient and substantial form, so that same may be easily and readily handled and so that the outer wooden case or box may be dispensed with, if desired.

With these and other objects in view, attention is called to the accompanying drawings, to be considered in connection with this specification, and wherein—

Figure I is a plan view showing a section of the cover removed; Fig. II is a side elevation; Fig. III a cross-sectional end view taken through the middle of the casket; and Fig. IV a sectional end elevation.

Referring now more particularly to the drawings, 1 represents the body proper of my improved casket, which may be stamped or formed from sheet steel or other suitable metal or material, and is shaped generally like the ordinary casket or coffin now used; the upper edges of the body 1 are formed trough-shaped as shown at 2, with the lower edge of the trough 2 falling below the top edge 3 of the casket 1, and the upper edge 4 of the trough 2 rising above the top edge 3 of the casket 1, so as to give the casket the S shaped edge around its upper portion, as shown. Along the upper edge 4 of the trough 2 are pierced the bolt or screw holes 5. It will be noted that with the said upper edge or rim of the casket so formed, the depressed portion 2 extending around the casket 1, serves as a hand hold and thus does away with the need of extra or additional handles, though such may be added if desired. Upon the body 1 of the casket so formed is placed the cover 6, which is formed so as to arch over the casket 1 by means of the bends 7. The outer edges of the said cover 6 at the point of juncture

with the edges 4 of the casket 1, are turned upwardly as shown at 8 so that the trough 9 so formed superimposes entirely around the casket 1 upon the top edge 3 of the said casket 1, and so that the lateral crevice 10 is left entirely around the casket 1 at the said point of juncture of the cover 6 with the body of the casket 1 and so that the hidden cavity 11 likewise extends entirely around the said casket 1 immediately below the edges of the cover 6. It will be noted that this cavity 11 may be filled with any suitable wax or other sealing material to exclude the air and moisture from the interior of the casket and so as to preserve the contents of the same. The interior of the casket 1 may be lined with hooks 12 for supporting any suitable drapery which may be used as a covering for the corpse inside. The upwardly turned edges 8 of the cover 6 are likewise pierced with holes 13 to correspond with the holes 5, and which are designed to receive the bolts or screws 14.

In actual use it will be seen that this method of construction of a burial casket affords a very simple, economical and efficient casket for the purpose. The corpse is placed within the casket 1, suitably draped, the cavity 11 is filled with sealing material, the cover 6 is placed on the casket, additional sealing material is poured along the crevice 10, the bolts 14 are screwed to place thereby drawing the edges 4 and 8 snugly together, compressing the sealing material and forcing it into every crevice and hole so as to effectually exclude all air and moisture for all time. The curved lower portion of the trough 2 forms a suitable hand hold, as stated, for use in depositing the casket in the grave. No outer box is required as the casket is enameled or otherwise treated so as to render it indestructible as against the action of the elements. The arched formation of the cover 6 enables it to resist any ordinary weight or pressure of earth.

Although I have herein set forth certain specific details for the construction of my improved casket, I reserve the right to modify same in minor points, not departing from the spirit of my invention, so as best to construct my improved casket to meet all practical demands and requirements.

What I claim as patentable is:
A burial casket consisting of an elongated

gated body portion having a trough-shaped rim with outer edge uprising above the same; an arch-shaped cover therefor having a trough-shaped edge turned upwardly toward the uprising edge of the body portion and forming an encircling crevice communicating with the outer trough of the outer rim aforesaid, both crevice and trough being designed to contain sealing material;

holes piercing the approaching edges of the 10 cover and body portion for the reception of bolts to draw the cover to the body portion and so as to compress the sealing material aforesaid.
